CLAIM

The ornamental design for a U-shaped handle for a nail file, as shown and described.

DESCRIPTION

FIG. 1 is a perspective view of a handle for a nail file with an abrasive pad in outline showing my new design;

FIG. 2 is a top view thereof;

FIG. 3 is a front view shown without the unclaimed abrasive pad;

FIG. 4 is a right side view thereof;

FIG. 5 is a left side view thereof;

FIG. 6 is a back view thereof; and,

FIG. 7 is a bottom view thereof.

The broken line showing of the abrasive pad is for illustrative purposes only and forms no part of the claimed design.
